[57] CLAIM

The ornamental design for a bucket cover, as shown and described.

DESCRIPTION

FIG. 1 is a perspective view of a bucket cover projected from the bucket showing my new design.

FIG. 2 is a perspective view thereof on the bucket.

FIG. 3 is a top view thereof.

FIG. 4 is a bottom view thereof.

FIG. 5 is a front view thereof.

FIG. 6 is a side view thereof.

FIG. 7 is a perspective exploded parts view thereof.

The broken-line showing of environmental structure in FIGS. 1 and 2 is for illustrative purposes only and forms no part of the claimed design.

The cross-line pattern which is partially shown for ease of illustration, represents a conventional fabric and is understood to repeat uniformly throughout the indicated area.
